DESIGN FOR A GARDEN WEEDE

Thomas E. Day, Sullivan Station, British
Columbia, Canada

Application May 14, 1946, Serial No. 129,692

Term of patent 14 years

(Cl. D35—2)

To all whom it may concern:

Be it known that I, Thomas E. Day, a citizen of Canada, residing at Sullivan Station, in the Province of British Columbia and Dominion of Canada, have invented a new, original, and ornamental Design for a Garden Weeder, of which the following is a specification, reference being had to the accompanying drawing, forming a part thereof.

Figure 1 is a front view of a garden weeder showing my new design.

Figure 2 is a side view thereof.

The rear of the garden weeder is like the front thereof.

I claim:

The ornamental design for a garden weeder, as shown and described.

THOMAS E. DAY.
